Primary Examiner — T. Chase Nelson*Assistant Examiner* — Jonathan J. Han(74) *Attorney, Agent, or Firm* — Banner & Witcoff, Ltd.(57) **CLAIM**

The ornamental design for a shoe, as shown and described.

DESCRIPTION

FIG. 1 is a front perspective view of a shoe showing my new design;

FIG. 2 is a side view thereof;

FIG. 3 is a rear perspective view thereof; and,

FIG. 4 is a cross sectional view taken through line 4-4 of FIG. 2.

The broken line immediately adjacent to the front of the shaded area defines the bounds of the claimed design and forms no part thereof. The broken lines showing the remainder of the shoe are for environmental purposes only and form no part of the claimed design.
